US00D849844S

(12) **United States Design Patent** (10) **Patent No.:** **US D849,844 S**
(45) **Date of Patent:** **** May 28, 2019**

(54) **HOUSING FOR A TOY**

(71) Applicant: **SPIN MASTER LTD.**, Toronto (CA)

(72) Inventor: **Anne N. Charbonneau**, North York (CA)

(73) Assignee: **SPIN MASTER LTD.**, Toronto (CA)

(**) Term: **15 Years**

(21) Appl. No.: **29/608,206**

(22) Filed: **Jun. 20, 2017**

(51) **LOC (11) Cl.** **21-01**

(52) **U.S. Cl.**

USPC **D21/398**

(58) **Field of Classification Search**

USPC ..... 27/1; 273/157 R; 446/309, 325, 396; D1/106, 107, 109, 118; D11/133, 157, D11/184; D2/869; D21/398, 483, 487, D21/488; D30/160; D6/597, 598; D7/301, 503, 509, 516, 599, 604, 619; D9/451, 617, 629, 666; D99/5, 37; D19/181; D14/216; D10/40

CPC A63H 13/03; A63H 23/10; A63H 33/005; A47G 19/28

(57) **CLAIM**

The ornamental design for a housing for a toy, as shown and described.

DESCRIPTION

FIG. 1 is a perspective view of the first embodiment of a housing for a toy, showing my new design;

FIG. 2 is a right side view thereof;

FIG. 3 is a top view thereof;

FIG. 4 is a front view thereof;

FIG. 5 is a left side view thereof;

FIG. 6 is a bottom view thereof;

FIG. 7 is a rear view thereof;

FIG. 8 is a perspective view of the second embodiment of housing for a toy thereof;

FIG. 9 is a right side view thereof;

FIG. 10 is a top view thereof;

FIG. 11 is a front view thereof;

FIG. 12 is a left side view thereof;

FIG. 13 is a bottom view thereof; and,

FIG. 14 is a rear view thereof.

In the drawings, the broken lines depict environmental subject matter only and form no part of the claimed design.

1 Claim, 6 Drawing Sheets
